(57) CLAIM

The ornamental design for a footwear platform, as shown and described.

DESCRIPTION

FIG. 1 is a perspective view of a footwear platform showing my new design;

FIG. 2 is a top plan view thereof;

FIG. 3 is a right side elevational view thereof;

FIG. 4 is a left side elevational view thereof;

FIG. 5 is a front elevational view thereof; and,

FIG. 6 is a rear elevational view thereof.

The broken lines showing a sandal throughout the views represent the environment in which the design resides, but does not form any part of the claim.
